UNITED STATES PATENT OFFICE

CHARLES L. PEIRCE, JR., OF PITTSBURGH, PENNSYLVANIA, ASSIGNOR OF ONE-HALF
TO HUBBARD AND COMPANY, A CORPORATION OF PENNSYLVANIA

METHOD OF MAKING SECONDARY RACKS

Application filed May 4, 1929. Serial No. 360,423.

This invention relates to the method of manufacturing insulator supports and more particularly to the method of manufacturing insulator supports of the type known as secondary racks such as are commonly employed for supporting a number of electric wires on an associated pole, wall or the like.

An object of the present invention is to provide an improved method of manufacturing secondary racks of the type set forth.

A further object is to provide an improved method of manufacturing a device of the type set forth from stock metal without waste of metal.

A still further object is to provide a method of manufacturing secondary insulator racks which consists in rolling a blank from stock metal and in stamping the completed rack from the blank.

These and other objects which will be apparent to those skilled in this particular art are attained by means of the invention illustrated in the accompanying drawings in which Figure 1 is a view in elevation of a blank formed during the process of manufacturing insulator racks in accordance with one embodiment of this invention. Fig. 2 is an end view of the blank shown in Fig. 1. Fig. 3 is a view similar to Fig. 1 showing the finished rack and Fig. 4 is a side elevation of the rack shown in Fig. 3. Fig. 5 is a partial view in elevation of a modification.

In the particular embodiment of this invention which has been chosen for the purposes of illustration a piece of metal stock is forged, by drop forging or rolling, to form a blank of elongated form and of irregular cross section as shown in Figs. 1 and 2. As illustrated, the shape to which the metal stock is forged is elongated and of irregular cross section so as to provide a blank having longitudinally extending, spaced side flanges 5 along each side thereof and these flanges are connected by a central web portion 6 joined to the inner edge of each flange by forwardly extending legs 7. The central web 6 is provided at spaced intervals with thickened portions or cross members 8 extending across the web and joining the forwardly projecting legs 7, each cross member being nearly equal

in thickness to the depth of such legs, see Fig. 2. The central web is also provided with longitudinally extending thickened portions 9 extending downwardly from each thickened cross member 8 and terminating in a rounded boss 10 which is formed in the web 6 just above the next cross member 8.

The blank so formed is then subjected to cutting and bending operations in which the elongated thickened portions 9 and bosses 10 are severed from the metal of the web 6 and bent upwardly to the positions shown in Figs. 3 and 4 wherein they extend outwardly from the cross members 8 to form insulator supporting arms 11 having perforated insulator supporting bosses 12 for supporting the spool type insulators threaded on the usual pin 13 in the usual manner. Perforations 15 can be formed in the base flanges 5 either during the forging or subsequent operations and such perforations may be used for cooperating with the usual supporting bolts. It will be apparent that a secondary rack of extremely rugged, and at the same time, simple construction is provided and that it is formed by a relatively few steps of standard metal working operations.

The finished rack includes a base formed by the spaced base members or outwardly extending flanges 5 which are connected with the forwardly projecting legs by the central cross members 8. The severing of the elongated arms from the central portion of the web and the bending of the arms upwardly provides the web with elongated openings 16 flanked by web portions 17 which are capable of cooperating with the usual through bolts commonly employed for supporting secondary racks, and are also especially adapted for use with the form of fastening described and claimed in my co-pending application Serial No. 564,275, filed May 27, 1922. The supporting parts which are subjected to the greatest strain are the heavy thickened cross members 8 and the integral, outwardly extending insulator supporting arms 11 which are formed integrally with the thickened cross members 8.

It will be apparent that the blank can be so formed, if desired, that the insulator sup-

porting arms 11 are connected to and extend outwardly from the front face of the thickened cross members 8, as shown in Fig. 5, instead of from the bottom thereof. Such an arrangement will provide a slightly greater reach of insulator supporting arm.

Although I have described in detail a specific form of this invention together with a particular series of specific steps for manufacturing the same, it will be apparent that various changes, additions, omissions and substitutions can be made therein without departing from the spirit of the invention or the scope of the appended claims.

What I claim as new and desire to secure by Letters Patent is:

1. The method of making insulator supporting structures which consists in forging metal stock to form an elongated blank having a cross section of varying thickness and subsequently forming outwardly extending insulator supporting arms from the thickened portions of the blank.

2. The method of making insulator supporting structures which consists in rolling metal stock to form a blank of channel form provided with outwardly extending side flanges and a central web having a cross section of varying thickness, partially severing the thickened portions from the web and bending said severed portions outwardly to form insulator supporting arms.

3. The method of making insulator supporting structures which consists in forging a piece of metal to form an elongated blank having spaced base members and a connecting web of varying cross section, partially severing the thickened portions from the web and bending said severed portions outwardly to form insulator supporting arms.

4. The method of making insulator supporting structures which consists in forging a piece of metal to form an elongated blank having side members connected by a central web provided with spaced cross members of substantially greater thickness than the metal of said web and elongated portions extending longitudinally of said web between said thickened cross members, severing said elongated portions from said web and bending said severed portions so as to extend outwardly from said cross members to form insulator supporting arms.

5. The method of making insulator supporting structures which consists in forging metal stock to form an elongated blank having spaced side members connected by an integral offset web having portions extending thereacross between said side flanges of substantially greater thickness than the metal of said web and connected to similarly thickened portions of less width than said web extending longitudinally of said web, said elongated portions terminating in a perforated boss, severing said elongated portions

and said boss from the metal of said web and bending said severed portions upwardly so as to provide a secondary rack having spaced base members connected by comparatively heavy integral cross members supporting outwardly extending integral insulator supporting arms.

6. The method of manufacturing insulator supporting structures which consists in rolling from stock metal an elongated blank having longitudinally extending side members connected by a web having cross members and longitudinal portions extending therefrom of greater thickness than said web, in severing the longitudinally extended portion of said cross member from said web and in bending outwardly said longitudinal portion from said web for forming insulator support arms for said structure.

7. The method of making insulator supporting structures which consists in rolling a piece of metal to form an elongated blank having spaced base members and a connecting web of varying cross section, partially severing the thickened portions from the web and bending said severed portions outwardly to form insulator supporting arms.

8. The method of making insulator supporting structures which consists in rolling metal stock to form an elongated blank having a cross section of varying thickness and subsequently forming outwardly extending insulator supporting arms from the thickened portions of the blank.

In testimony whereof, I have hereunto subscribed my name this 27th day of April, 1929.
